UNITED STATES PATENT OFFICE.

ANTON H. RINTELMAN, OF CHICAGO, ILLINOIS.

NEEDLE FOR TALKING-MACHINES.

1,271,224.

Specification of Letters Patent.

Patented July 2, 1918.

Application filed January 4, 1915. Serial No. 324.

To all whom it may concern:

Be it known that I, ANTON H. RINTELMAN, a citizen of the United States, and a resident of Chicago, in the county of Cook and State of Illinois, have invented certain new and useful Improvements in Needles for Talking-Machines, of which the following is a full, clear, and exact specification.

My invention is concerned with sound-reproducing machines, and more especially with a novel needle which is so constructed as to be extremely durable.

To illustrate my invention, I annex hereto a sheet of drawings, in which the same reference characters are used to designate identical parts in all the figures, of which—

Figure 1 is a side elevation of the sound box of a graphophone having my improved needle mounted therein;

Fig. 2 is a detail of the same in central, vertical section, on an enlarged scale; and

Fig. 3 is a perspective view of the needle detached.

The needle 10 is constructed of a bar of crystalline material, such as agate, emerald, garnet, ruby, or of diamond, etc., and is preferably triangular in cross section and of a size about equal to that of the well known fiber needle. To produce a plurality of

points, I grind in one or both ends the concavities 11, which may run into each other, or so nearly so as to form on each end three points 12, which are preferably made quite fine, and which, being very hard, can be used a very long time without material wear on either the record or the needle. As each point is extremely durable, with the three or six points, the needle can be used almost indefinitely, without being renewed or re-

ground. These points are blade-like in a vertical plane through them and along the line of the groove of a Victor or Columbia record, thus enabling them to penetrate said grooves and coöperate as fully with that

type of a record as an ordinary steel needle. To procure the greatest possible amount of power from this needle, I secure one end by the said screw 20, as shown in Figs. 1 and 2, in the needle-receiving aperture 13

50 in the bottom of the needle-arm 14, which

is suitably fulcrumed in bearings 15 on the edge of the sound box 16, and has its upper end connected to the center of the diaphragm 17, in the customary manner. This gives a very loud tone.

In case a softer tone is required, any suitable mounting of the needle for muting the needle may be employed.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States, is:

1. A needle for sound reproducing instruments which consists of a bar of crystalline material, polygonal in cross section, and having blade-like points on one end formed by channels placed in the sides of the bar, said channels commencing at some distance 75 from the end of the bar and increasing in depth and width to said end, the width, depth and shape of the channels at the end being such as to form on the end a figure consisting of radiating pointed portions with 80 the tips of the pointed portions located at the edges of the bar.

2. A needle for sound reproducing instruments which consists of a bar of crystalline material, having blade-like points on one 85 end formed by channels placed in the side of the bar, said channels commencing at some distance from the end of the bar and increasing in depth and width to said end, the width, depth and shape of the channels 90 at the end being such as to form on the end a figure consisting of radiating pointed portions.

In witness whereof, I have hereunto set my hand and affixed my seal, this seventh day of December, A. D. 1914.

ANTON H. RINTELMAN.
